[57] CLAIM

The ornamental design for a door for an electrical loadcenter, as shown and described.

DESCRIPTION

FIG. 1 is a top, front and right perspective view of a door for an electrical loadcenter showing our new design;

FIG. 2 is a rear elevational view thereof;

FIG. 3 is a left elevational view thereof;

FIG. 4 is a bottom plan view thereof; the top plan view being a mirror image; and,

FIG. 5 is a rear and upper right perspective view thereof.

Fig. 1
